UNITED STATES PATENT OFFICE.

KARL KIEFER, OF CINCINNATI, OHIO.

FILTER.

SPECIFICATION forming part of Letters Patent No. 579,586, dated March 30, 1897.

Application filed May 22, 1896. Serial No. 592,675. (No model.)

To all whom it may concern:

Be it known that I, KARL KIEFER, a citizen of Germany, and a resident of Cincinnati, in the county of Hamilton, in the State of 5 Ohio, have invented a new and useful Filter, of which the following is a description.

My invention relates to improvements in filters which apply paper or similar pulp as a filtering medium.

10 The objects of my improvements are, first, to simplify the construction of such a filter; second, to effect an even homogeneous layer of pulp, and, third, to simplify the operation of filtering. I attain these objects principally 15 by using a specially-constructed filtering-plate, which is illustrated by the accompanying drawings.

Figure 1 is a vertical section of the entire machine. Fig. 2 is a top view of half a plate. 20 The other half is symmetrical and is not shown on account of limited space.

Similar letters refer to similar parts throughout the views.

The top plate A and the bottom plate B, 25 held together by bolts, are the elements between which the filtering-plates C are contained. Of the filtering-plates there may be one or more applied without changing the working of the apparatus, only different-sized 30 bolts have to be used.

I will give a description of the most important part—the filtering-plate—first, and then describe the operation of the machine afterward.

35 The filtering-plate C has the shape of a circular plate, with a proportionately low cylindrical border on its periphery. The center of the plate has the opening n. Concentrically with the opening n there is another 40 low cylindrical wall of about the same height as the outside border. The ring-shaped space between these two borders serves for the reception of the pulp mass i. The bottom of this ring-shaped space is cut out in the 45 shape of concentrical rings whose cross-section is similar to the cross-section of a thread. They are plainly shown in Fig. 2. These thread-like rings are intersected by channels f. The prolongations of the channels f 50 are small holes h, which connect the ring-shaped space between the borders with the central opening n. The top and bottom of

the outside border, also the top and bottom of that part of the filtering-plate surrounding the opening n, are formed to receive the ring-shaped gaskets d and e, by means of which the two filtering-plates can be tightened, respectively, so as to prevent any liquid contained within the filtering-plate to escape outside the cylindrical borders and in the opening n.

The ring-shaped space of the filtering-plate C between the inner borders and that central part carrying the gasket e is perforated with vertical holes k, which, however, do not cross 65 the small holes h, but are suitably placed between them.

The opening m in the bottom plate B serves for the admission of cloudy liquid.

The opening n in the bottom plate corresponds with the central opening of all the filtering-plates C.

Before I go to a description of the operation of the machine as a whole I will describe how to produce the ring-shaped mass of pulp i in 75 the filtering-plate.

A ring-shaped diaphragm g is put on top of the threaded part of the filtering-plate. (This diaphragm may consist of muslin or fine metal gauze.) Then a certain amount of paper-pulp, 80 which has been previously dissolved in water, is poured on top of the diaphragm. The water contained in the pulp will then soak through the diaphragm, but the fibers of the paper are retained, the holes of the diaphragm being 85 too small for them to pass through. The pulp mass i now forms a loose layer on top of the diaphragm between the cylindrical borders. This loose layer now is exposed to the pressure from above by a suitable press-plate pressing 90 all the water out of the pulp and forming the homogeneous layer i between the cylindrical borders. The water pressed out of the pulp and later on also the liquid to be filtered have to go through the diaphragm in the triangular channels formed by the threads, from there to the intersecting channels f, and through the openings h in the central hole n.

The operation of the filter is as follows: One or more filtering-plates having been provided with a pulp layer in the described manner, they are put on the base plate B with gaskets e and d between the borders of each other and covered with the top plate A. Then

the top and base plates are drawn together by means of bolts. The liquid then enters at *m*, rises through hydrostatic pressure through the holes *k* of all the filtering-plates, (indicated on plate C by means of arrows.) The plates are so constructed that when put together there is a little space between the inside border *l* and the bottom part of the plate above through which the liquid to be filtered can get over the pulp layer of each filtering-plate. The liquid now passes through the filtering medium, leaving all impurities in same, then through the thread-like rings of the filtering-plate, and collects at the channels *f*, and from there through the holes *h* to the central opening *n* of the machine.

It is readily to be seen from the drawings that the central opening *n* is sufficiently separated from the ascending cloudy liquid by means of 20 gaskets *e*. The openings *m* and *n* may also be in the top plate without changing the working of the filter.

The number of channels *f* in the filter need not be six, as shown in the drawings, but may 25 be unlimited.

Instead of bolts, as shown in the drawings, other means to tighten the apparatus may be chosen.

Some of the advantages attained by the 30 foregoing-described invention are that, first, the pulp layer of the filtering-plate C can be pressed nearly dry, as the threads of the filtering-plate withstand any pressure exerted upon them; second, the filtering-plates are 35 interchangeable; third, for small quantities of filtered liquid a few may be used, and more for large quantities; fourth, the capacity of the machine compared with the filtering-surface is reduced, and, fifth, the liquid to be filtered passes over the pulp layers evenly.

What I claim as my invention, and desire to secure by Letters Patent, is—

1. In a filter a combination of a bottom plate and a top plate, with an inlet and outlet constituting a frame, and one or more congruent 45 and interchangeable circular filtering-plates with inlets and outlets centrally and symmetrically arranged, and containing the filtering medium in a ring-shaped flat layer, said filtering-plates having ring-shaped corrugations 50 in their bottom part against which the filtering medium rests; substantially as set forth above.

2. In a filter a combination of a bottom plate and a top plate, with an inlet and outlet constituting a frame, and one or more congruent 55 and interchangeable circular filtering-plates with inlets and outlets centrally and symmetrically arranged, and containing the filtering medium in a ring-shaped flat layer, said 60 plates having ring-shaped corrugations serving as outlet-channels for the clear liquid intersected by channels *f*, communicating with the central outlet-opening *n*, and having holes *k* for the cloudy liquid concentrical and 65 symmetrical with the outlet-opening *n*; substantially as set forth above.

3. In a filter a combination of a bottom plate and a top plate with an inlet and outlet, constituting a frame and one or more similar 70 circular filtering-plates, having two concentrical cylindrical borders and a corrugated bottom part, between which the ring-shaped filtering-layer is contained; substantially as set forth above.
